which were selected earlier and thus had evaluations over a longer period of time than Yellow Brioso.

The following traits have been repeatedly observed and are determined to be basic characteristics of Yellow Brioso, which, in combination, distinguish this Chrysanthemum as a new and distinct cultivar:

1. Flat capitulum form.
2. Daisy capitulum type.
3. Yellow ray floret color.
4. Diameter across face of capitulum of 108 to 114 mm when fully opened, when grown as a single stem cut mum.
5. Photoperiodic flowering response to short days of 52 to 53 days.
6. Plant height, with 7 to 14 long days after planting rooted cuttings prior to start of short days and with no growth regulator applications, ranges from 99 to 102 cm when grown as a single stem cut mum.

The accompanying photographic drawing is a view of a single stem of Yellow Brioso, with the colors being as nearly true as possible with illustrations of this type. The precise ray floret color of Yellow Brioso has not been captured in the photograph. The flower typified by the lowest full flower in the center of the photo is more pale yellow, and the peripheral flowers display too much gold. The true color of Yellow Brioso is an intense bright yellow, the color value of which is correctly noted below.

Of the commercial cultivars known to the inventor, the most similar in comparison to Yellow Brioso is the parent cultivar Brioso. All traits of Yellow Brioso are similar to those of Brioso, except for the ray floret color, and plant height. The ray floret color of Yellow Brioso is a bright yellow, while the ray floret color of Brioso is described as purple. In two flowering evaluations the height of Yellow Brioso was described as 5 cm shorter than the height of Brioso.

In the following description color references are made to the Royal Horticultural Society Colour Chart. The color values were determined on plant material grown as a single stem spray cut mum in Salinas, Calif. on Jun. 20, 1990.

Classification:

Botanical.—*Dendranthema grandiflora* cv Yellow Brioso.

Commercial.—Flat daisy spray cut mum.

INFLORESCENCE

A. Capitulum:

Form.—Flat.

Type.—Daisy.

Diameter across face.—108 to 114 mm when fully opened.

B. Corolla of ray florets:

Color (general tonality from a distance of three meters).—Yellow.

Color (upper surface).—6B to 6C.

Color (under surface).—6C to 6D, slightly overlaid with bronze tinges, closest to 168D to 169A.

Shape.—Oblong.

C. Corolla of disc florets:

Color (mature).—14A.

Color (immature).—144B.

D. Reproductive organs:

Androecium.—Present on disc florets only; scant pollen.

Gynoecium.—Present on both ray and disc florets.

PLANT

A. General appearance:

Height.—99 to 102 cm when grown as a single stem cut mum with 7 to 14 long days after planting rooted cuttings prior to start of short days and no growth regulator applications.

B. Foliage:

Color (upper surface).—147A.

Color (under surface).—147B.

Shape.—Lobed and slightly serrated.

I claim:

1. A new and distinct Chrysanthemum plant named Yellow Brioso, as described and illustrated.
